GEORGE W. HAHN, OF INDIANAPOLIS, INDIANA.

COMBINATION DUSTER AND SCRUBBER.

1,198,839.

Specification of Letters Patent. Patented Sept. 19, 1916.

Application filed January 24, 1916. Serial No. 73,896.

To all whom it may concern:

Be it known that I, GEORGE W. HAHN, a citizen of the United States, residing at Indianapolis, in the county of Marion and State of Indiana, have invented a new and useful Combination Duster and Scrubber, of which the following is a specification, reference being had to the accompanying drawings, and to the letters and figures of reference marked thereon.

This invention relates to a dusting brush and a scrubbing brush combined and provided with a water-supplying conduit, the invention having reference more particularly to a water-supplied brush that is designed for rapid work in cleaning the running gear of automobiles or muddy surfaces of other vehicles or other structures.

An object of the invention is to provide an improved combination dusting and scrubbing brush that shall be so constructed as to be capable of withstanding the deteriorating effects of water, and which shall be simple and inexpensive so as to be suitable for general use.

Another object is to provide a strong and durable brush of such construction as to permit the renewal of the bristles or brush fibers while saving the remainder of the brush for future use, in the interest of economy.

A further object is to provide a metallic brush back that shall be of light weight and strong and capable of holding the maximum number of bristles or fibers to form the brush, in order that the brush structure while having an unobtrusively small back shall be adapted to cover a large amount of surface in operation.

A still further object is to provide an improved brush frame having a conduit therein for conducting water to wet the brush and the surfaces to be cleansed and be capable of supplying sufficient water for rinsing the scrubbed surfaces, which frame shall be detachable from the brush back in order to permit renewal of the brush without discarding the entire frame of the brush, in order that the brush shall be not only efficient and durable but also economical in use.

With the above-mentioned and other objects in view, the invention consists in an

improved conduit-equipped brush having a novel back and frame, and novel means for securing the brush bristles or the like to the back; the invention consisting further in the parts, and combinations and arrangements of parts, as hereinafter particularly described and further defined in the accompanying claims.

Referring to the drawings, Figure 1 is a perspective view of the improved duster and scrubber; Fig. 2 is a perspective view of the principal portion of the frame of the duster and scrubber; Fig. 3 is a longitudinal central sectional view of the duster and scrubber; Fig. 4 is a sectional elevation approximately on the line A A on Fig. 3; Fig. 5 is a section, partially broken away, approximately on the line B B on Fig. 4 looking upward; Fig. 6 is a perspective view of the main part of the improved brush back inverted; and, Fig. 7 is a perspective view of the inner part of the brush back inverted.

Similar reference characters on the different figures of the drawings indicate corresponding elements or features of construction herein referred to.

In practically carrying out the objects of the invention a novel brush back is provided which comprises a main or outer part that is composed of sheet metal and bent so as to be approximately U-shaped in cross section, so that the part has an arched top portion 1 from which extend two flat side portions 2 and 3 of the desired length, one side portion having flexible fingers 4 and 5 on its ends, the opposite side portion having similar fingers 6 and 7 on its ends, the fingers 90 projecting from the ends before uniting the parts of the back. The inner part of the back also is composed of sheet metal and bent so as to be approximately U-shaped in cross section but of less width and height 95 than the outer part, both parts being equal in length, the inner part thus having an arched upper portion 8 from which extend two flat sides 9 and 10. One side 9 has notched corners so as to form downwardly 100 facing shoulders 11 and 12, the opposite side being similarly notched at its ends to form downwardly-facing shoulders 13 and 14, the notches or recesses in the ends of the sides being designed to receive the fingers of the outer part. Suitable brush material is em-

ployed, such as bristles or wood fibers arranged transversely of the main part, the middle portions of the bristles or fibers being pressed into the main part as a layer 5 15 and against which the inner part is forced, after which the fingers of the main part are bent over across the end portions of the layer and inward against the inside of the sides 9 and 10 or the inner part, the 10 fingers being in contact with the shoulders of the inner part and securely locking the inner part in place and enabling it to securely retain the brush material which projects from the back parts, so as to form two associated 15 brush rows 16 and 17 of bristles or the like. Thus constructed the brush is suitable for hand use for various purposes.

In order to supply the brush with water, the more readily to loosen and remove mud 20 from surfaces, a tube 18 is provided and inserted endwise in the inner part of the brush back so as to be behind the fingers that are on the inside of the lower portions of the sides 9 and 10, the fingers retaining the tube 25 against lateral displacement. A collar 19 is placed on one end of the tube and suitably secured thereto, as by expanding the end of the tube in the collar, the latter being brought up to the end of the brush back, the 30 tube being sufficiently long to extend beyond the opposite end of the brush back to adapt the tube to constitute a part of the frame for holding and using the brush. The end of the tube that has the collar on it is closed, 35 preferably by means of a wooden plug 20 driven therein, and in order to guard against the metallic brush back marring finished surfaces a guard or cover 21 is provided which may be composed of leather or other 40 yielding substance in the form of a disk which is placed against the collar 19 and secured thereto by means of a nail 22 driven through the disk and into the plug 20. The tube 18 which forms a water-supplying 45 conduit has a suitable number of apertures 23 in the normal under portion of its wall so as to deliver water to the brush material. A handle member 24 is placed on the projecting portion of the tube against the rear end 50 of the brush back and secured thereto by means of a screw-threaded nut 25 which is screwed onto the tube and tightly secures the latter to the brush back, the nut having a flange 26 thereon provided with internal 55 screw-threads 27 so as to constitute a coupling member to be connected to the coupling device of a water-supplying hose, a packing washer 28 being placed in the coupling member.

60 In practical use the brush may be used for a great variety of purposes, either dry or wet, and is especially adapted to be inserted between the spokes of vehicle wheels, or other limited spaces, for removing dust in

dry condition or for scrubbing and loosening 65 mud and for rinsing off the scrubbed surfaces, the supply of water to the brush being regulated as may be desired, so that after loosening the mud ample water under pressure may be furnished for floating off the 70 loosened mud.

Having thus described the invention, what is claimed as new is—

1. A duster including an arched main back part having fingers on the two opposite ends 75 thereof, an arched inner back part in the main back part and having recesses in its ends receiving the fingers and thereby being secured to the main part, and brush material arranged in a layer between said back parts 80 and secured thereto, the material extending beyond said parts.

2. A duster and scrubber including an arched main back part, an arched inner back part in the main back part, brush material 85 arranged in a layer between the back parts and secured thereto, the material extending beyond said parts, a tube in the inner back part and extending beyond the ends thereof, the tube having apertures in its wall between 90 the sides of the inner back part, a collar secured to one end of the tube and in contact with one end of the back parts, and a retaining device on the tube in contact with the opposite ends of the back parts. 95

3. A duster and scrubber including an arched main back part having fingers on the two opposite ends thereof, an arched inner back part in the main back part and having shoulders in its ends engaged by said 100 fingers and thereby secured to the main part, brush material arranged in a layer between said back parts and secured thereto, the material extending beyond the parts, a perforated tube in the inner back part and extending beyond the ends thereof, the tube 105 extending behind said fingers, a collar secured to one end of the tube and in contact with one end of the main back part, a yielding cover secured to and covering the front 110 of the collar, a handle member on the tube in contact with the opposite end of the main back part, and a nut secured to the tube in contact with the handle member and having a hose-coupling member thereon. 115

4. A duster and scrubber including an arched main back part having fingers on the two opposite ends thereof, an arched inner back part in the main back part and having recesses in its ends receiving the fingers and 120 thereby being secured to the main part, bristle-like material arranged in a layer between said back parts and secured thereto, the material extending beyond the parts, a tube in the inner back part and extending 125 beyond the ends thereof, the tube having apertures in its wall between the sides of the inner back part, a collar secured to one end

of the tube and in contact with one end of the main back part and the fingers thereof, a plug secured in the end of the tube adjacent to the collar, a yielding cover secured to the plug and covering the front of the collar, a handle member on the tube in contact with the opposite end of the main back part and the fingers thereof, and a nut secured to the

tube in contact with the handle member and having a hose-coupling member thereon. 10

In testimony whereof, I affix my signature in presence of two witnesses.

GEORGE W. HAHN.
